UNITED STATES PATENT OFFICE.

WILLARD F. RICHARDS, OF BUFFALO, ASSIGNOR TO THE GOULD COUPLER COMPANY, OF NEW YORK, N. Y.

DESIGN FOR A THRESHOLD-PLATE.

SPECIFICATION forming part of Design No. 23,705, dated October 16, 1894.

Application filed September 11, 1894. Serial No. 522,757. Term of patent 14 years.

To all whom it may concern:

Be it known that I, WILLARD F. RICHARDS, a citizen of the United States, residing at the city of Buffalo, in the county of Erie and State of New York, have invented a new and original Design for Threshold-Plates for Railway-Cars, of which the following is a specification.

This design relates to the ornamentation of the threshold plates which are employed principally in vestibule cars, for covering the joint between the horizontal wing or rearward extension of the buffer and the floor of the car platform.

The design is illustrated in the accompanying drawings, in which—

Figure 1 is a plan view of a threshold plate embodying my design. Fig. 2 is a fragmentary view thereof, on an enlarged scale. Fig. 3 is a cross section of the same in line 3—3, Fig. 1, on an enlarged scale.

Like letters of reference refer to like parts in the several figures.

The leading feature of my design consists in a large depressed panel or field A of oblong form arranged upon the middle portion 25 of the threshold plate and two smaller depressed panels B B of similar form arranged on opposite sides of the large central panel. The remaining raised portions of the surface of the plate which surround and separate 30 these three panels are ornamented with a diaper pattern, composed of pyramidal figures c of diamond or lozenge-shaped outline. A row of holes d extends along one of the longitudinal margins of the threshold plate. 35

What I claim is—

The design for a threshold plate herein shown and described.

Witness my hand this 10th day of September, 1894.

WILLARD F. RICHARDS.
